GEORGE B. THOMAS, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

CANOPY FIXTURE.

Application filed May 14, 1925. Serial No. 30,187.

My invention relates to canopy fixtures, and particularly to canopy switch installations. The object of my invention is to provide an installation in which the switch structure and mounting are of such character that the switch may be housed within the canopy without displacement or deformation of the latter. The mechanism of the switch may be of any character, but I prefer a pull switch, the flexible actuating chain or cord of which passes through the canopy. The installation is particularly applicable to lighting fixtures, the switch being connected in the lamp circuit to control the latter.

The present application is a continuation in part of my copending application Serial No. 460,920, filed April 13, 1921.

The invention is illustrated in the accompanying drawings, in which—

Fig. 1 is a vertical section through portion of a canopy fixture showing the switch housed in one position within the canopy;

Fig. 2 is a similar view showing the switch housed in another position in the canopy;

Fig. 3 is a section on the line 3—3, Fig. 1;

Fig. 4 is a section on the line 4—4, Fig. 2; and

Fig. 5 is a perspective of another mounting.

A lighting fixture installation is illustrated as typical of the invention. An installation of this character usually comprises an outlet box 6 through the side opening 7 at which the wire main 8 enters. Secured to the base of the box is the usual fixture stud 9 with hickey 10 and fixture pipe 11, through which the wires 12 and 13 are led from the lamp sockets (not shown) to the junction box. The latter is provided with the usual cover 14, the neck 15 of which projects through the plaster 16 of the ceiling or wall, and permits access to the interior of the box for making the necessary connections to the wires 17 and 18 of the cable 8.

Surrounding the fixture pipe 11 and secured thereto by a set screw 19 is a canopy 20 of conventional type, which houses in the junction box connections and imparts a finish to the wall end of the fixture. The particular shape of the canopy is of course subject to innumerable variations, but it is ordinarily such that sufficient room is afforded between it and the fixture pipe to accommodate a switch having sufficient current

breaking capacity for use in a lighting installation. Moreover, switches of ordinary type are not equipped with suitable means for securing the same within a canopy. It has consequently been customary to control the lighting circuit either by a wall switch remote from the fixture, or by a switch of ordinary construction mounted on the exterior of the canopy, or nearby the latter, and seriously impairing the general appearance of the installation.

To meet this situation, I have devised a switch of such contour that it may be accommodated within the canopy, while at the same time its mechanism is such that it can safely control the lighting current. I also associate with the switch suitable means for securing it in fixed position within the canopy.

In the form here illustrated, the body of the present switch, which has a generally ovoid shape in plan, and is of slight thickness in side elevation, comprises a pair of insulating buttons 21 and 22, recessed on their meeting faces to afford a switch chamber. The switch mechanism mounted within this chamber may be of any suitable sort which will safely control the lighting circuit, for example that shown in the patent to Renholdt, No. 1,400,376, December 13, 1921, which need not be described except to point out that it is actuated by the pull chain 28. The pig tail leads 33 and 34 extend to the stationary terminals of the switch and project from one end of the switch opposite that from which the pull chain 28 emerges. The free ends of the pig-tails 33 and 34 are led out in opposite directions through closely confining apertures in the side wall of the button 22, and their ends are bared to facilitate connection with one of the wire mains, 18, and one of the fixture wires, 12, thus electrically interposing the switch in the lighting circuit. After the pig-tails have been connected to the switch terminals (not shown) and the switch mechanism assembled between the buttons, the latter are permanently secured together by suitable screw bolts 35, the heads and nuts of which are waxed in to prevent ready access thereto.

The button 21 is provided with a central boss 36 which may be pierced at 37 to permit access to the usual adjustable abutment 38 for the ratchet spring (not shown). In the

area surrounding the boss 36 I secure a plurality of tapped rivets (not shown) for a purpose about to be described.

While it is possible to arrange the switch within the canopy without supporting it otherwise than by permitting it to wedge itself between the fixture pipe 11 and the wall of the canopy, this does not afford a workmanlike installation. In order to secure the switch properly within the canopy, I provide bracket means of any suitable sort, adapted to be attached to the switch on the one hand, and to the fixture on the other hand, to hold the switch in fixed position within the canopy, and to relieve the latter of any strains incident to the operation of the switch mechanism. In the form shown in Fig. 1, the bracket 41 comprises a piece of strap metal forked at one end 42 to straddle the boss 36, and apertured to receive screws 43 which pass through holes in the forked end of the strap, and enter the tapped rivets to clamp the bracket to the switch. At its opposite end the bracket is offset at 45 to afford a securing arm pierced to fit over the hub 46 of the stud 9, against which it is clamped by the screwing-up of the hickey 10.

When a bracket of this type is used, the switch is held with its nose end projecting downward into the narrower area of the annular chamber afforded between the pipe 11 and the canopy 20. To accommodate the switch to this restricted area, the nose of the button 22 (which is faced outward toward the canopy wall) is beveled at 47 to afford ample clearance between the canopy wall and the switch at this point. For the same purpose the button 21 (which lies against the pipe 11) is preferably grooved at 48 (Fig. 4) at its nose end to permit the switch to hug the pipe at this point and thus further increase the clearance between the canopy wall and the switch body.

In Figs. 2 and 4 I have shown a modified construction of the bracket, adapted to clamp upon the fixture pipe 11. One element 49 of the bracket is integral with the fork 42 secured to the switch, while the co-operating member 50 of the clamp embraces the pipe, the clamping screws 51 passing through the offset ends of the bracket members, and serving to hold the switch in horizontal position. The beveled nose 47 of button 22 now permits this portion of the switch body to enter the restricted area afforded between the base of the canopy and the ceiling or wall 16.

The switch actuating member may be of any suitable type. Where it is of the pull-chain type illustrated, I preferably arrange between the buttons 21 and 22 at the nose ends of the latter, a double funnel-shaped bushing 52, which is clamped in position on the assembly of the buttons.

To permit the chain to make a free exit from the canopy, the latter is punched through either at its lower end, as in Fig. 1, or adjacent its base, as in Fig. 2, and a guide bushing 53 secured therein. The insertion of this bushing is facilitated if it is formed in two parts, which are assembled with the canopy by inserting one part in the hole punched in the canopy, and screwing the other part thereon from the opposite face of the canopy wall. The bushing is self-sustained in position by its flared ends.

In Fig. 5 still another form of securing bracket is illustrated which closely approaches that shown in Figs. 2 and 4. As in the latter construction the bracket comprises a pair of arms 49 and 50, the latter independent of the former and clamped around the pipe 11 by the draw-up screws 51. The portion 49 of the clamp is integral with the body section 54, which in this instance is not forked as in the construction previously described, but is of plate-like construction and attached to the lower face of the button 21 in the same manner as that previously described. It is centrally recessed to accommodate the boss 36 so that free access to the adjusting member 38 for the switch spring mechanism is afforded.

With this construction the switch may be located closer to the conduit 11 than is possible in the construction shown in the Fig. 1, and it may also be located nearer to the lower end of the canopy 20, thus effecting an economy in the length of the pull chain 28. The construction is otherwise similar to that above described.

It will be recognized that whether mounted in one position or the other, or in some way other than that indicated, the switch and its mounting are of such construction and contour that it is readily accommodated within the canopy to one side of its axis, between the pipe 11 and the canopy wall, and affords an installation of greatly improved appearance, as well as of sound workmanlike electrical construction, adapted to standard canopy contours without alteration of the latter.

Various modifications in detail will readily occur to those skilled in the art, which do not depart from what I claim as my invention.

I claim—

1. An electric lighting fixture comprising an outlet box, a conduit suspended therefrom, a canopy through which the conduit passes, in combination with a switch having a supporting bracket, means for securing the same on the conduit with the switch located between the canopy wall and conduit, and switch operating means passing through the canopy.

2. An electric lighting fixture comprising a wire conduit, a canopy through which the

conduit passes, a switch body having a narrow nose, a flexible switch operating member emerging from said nose, and bracket means attached to a flat face of the switch body and having a portion projecting from said face and adapted to engage the conduit to support the switch between the canopy wall and conduit with the nose of the switch in an area of restricted dimensions, said flexible operating member passing through the canopy.

3. An electric lighting fixture comprising a fixture support, a wire conduit carried thereby, a canopy concealing said support, a switch arranged to one side of said wire conduit within said canopy and having an insulating body, a flexible pull member extending from one end of said body and passing through the canopy for manual operation of the switch mechanism, a supporting bracket directly attached to the switch body and extending therefrom in opposite direction to that of the pull member, and means associated with said bracket for rigidly se-

curing the switch body in position without 25 imposing load on the canopy.

4. An electric fixture comprising a wire conduit, means for supporting the same including a member apertured to admit lead wires to the conduit, in combination with 30 a switch comprising a relatively shallow insulating body of reduced dimensions at one end, a flexible switch operating member emerging from said end of the switch body, pig-tail connections emerging from the opposite end of said body at one face thereof, and a supporting bracket secured to the opposite face of said switch body and projecting therefrom in a direction opposite the flexible pull member and adapted at its free 40 end to support the switch to one side of the conduit, together with a canopy secured to the conduit and housing the fixture support and switch, said flexible switch-operating member passing through the canopy. 45

In testimony whereof I have signed my name to this specification.

GEORGE B. THOMAS.
